UNITED STATES PATENT OFFICE

98,930

DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corporation of New Jersey

Application December 2, 1935, Serial No. 59,851

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The area contained within the dot and dash lines constitutes one design unit, which unit is repeated in the relation indicated over the entire face of the fabric.

The characteristic feature of the present design

resides in a base fabric comprising a series of wavy stripes running substantially parallel to one another throughout the entire fabric and series of groups of alternating long and short knobby ridges arranged in rows on said base fabric in raised relation thereto and extending substantially at right angles relative to said stripes, said ridges being arranged in staggered relation with respect to adjacent ridges resulting in a herringbone appearance.

I claim:

The ornamental design for a textile fabric or similar article of manufacture substantially as shown and described.

JOHN F. GAUL, JR.
